UNITED STATES PATENT OFFICE

JACK E. LINEBERGER, OF CHARLOTTE, NORTH CAROLINA

DISPLAY DEVICE

Application filed November 1, 1929. Serial No. 404,094.

This invention relates to an exhibiting device and more especially to a device adapted to rotate, and having a face thereon on which articles of merchandise may be exhibited together with a casing in the rear of the exhibiting device divided into compartments corresponding to the section shown on the face of the exhibiting device, so that when a given article is desired by a customer that 10 the article may be withdrawn from the section of the compartment corresponding to the section on the face of the exhibiting device.

An object of my invention is to provide an 15 exhibiting device having a revolving exhibiting member in combination with a casing similar to the exhibiting member divided into compartments corresponding with the sections marked off on the face of the exhibiting 20 member, said compartments being adapted to have stored therein the articles exhibited by the exhibiting face of the device.

Another object of my invention is to provide a revolving exhibiting device divided 25 into sections with means for securing articles of merchandise and other objects to the base of the exhibiting device, said exhibiting device having mounted concentric therewith a storage compartment, said storage 30 compartment being divided into sections corresponding to the sections on the face of the exhibiting device, in which a stock of the specimens exhibited on the face of the exhibiting device may be stored.

35 Some of the objects of my invention having been stated other objects will appear as the description proceeds, when taken in connection with the accompanying drawings, in which—

40 Figure 1 is a front elevation of my device; Figure 2 is a side elevation of my device; Figure 3 is a cross-sectional view taken along the line 3—3 in Figure 1;

45 Figure 4 is a rear view of my device showing a portion of the cover member broken away;

Figure 5 is an enlarged detail view showing the manner of attaching the articles to the face of the exhibiting sign;

50 Figure 6 is another enlarged detail view

showing the manner in which a plurality of objects may be secured to the face of the exhibiting device.

Referring more specifically to the drawings the numeral 10 indicates a base member which has secured therein a standard 11 and to the top of standard 11 is secured the bearing member 12 which has rotatably mounted therein the shaft 13, one end of said shaft having secured thereon a disk member 14 55 with the pulley member 15 secured to the back portion thereof, said member 14 being secured on the shaft 13 by means of the nuts 16 and 17, and the face portion of this member 14 being adapted to have secured thereto a plurality of articles of merchandise 18 and the face portion of this device is divided into sections A, B, C, D, E, F, G, H, I, J, K, L, M, N, O, P, Q, R around the outer periphery thereof, and the inside portion is divided 60 into the compartments 19, 20, 21, 22, 23, 24, 25, 26 and 27, and in Figure 1 I have shown a plurality of articles of merchandise 18 secured thereto, and in this figure I have shown paint brushes but I desire it to be understood 65 that any articles of merchandise may be exhibited on this exhibiting device. The single articles of merchandise are adapted to be secured to the portion 14 by means of the clamping bolt 30 which has the nut 31 thereon, on the inside of the device, and in the inside portion of my device I show the elongated U-bolt member 32 which has a nut 31, 70 inside thereof whereby a plurality of articles 75 may be secured in one section.

80 The pulley 15 has secured thereon the belt 33 which is also mounted on the small pulley 34 of the electric motor 35, which is secured on the standard 11 by means of the support 36 being secured around the standard 11. 85 The member 12 has the flange 37 therearound, which is adapted to serve to limit the movement of the compartment member 40 which is adapted to be rotated by hand on the portion 41. This casing or storage compartment 90 40 has the side wall portion 42, and the circular outer portion 43 with the circular partition member 44, and the hub 45, said hub member being adapted to be rotated on the bearing portion 41. The circular member 43 95 100

is integral with the side wall portion 42 and has the inturned match 46 therearound and the circular member 44 has the portion 47 secured thereto with partition member 49 dividing the interior of the casing 40 into compartments each equal in number and identical in size to the sections A to R on the face 14, and also dividing the portions between the circular portion 44 and the hub portion 10 45 into compartments equal in number and identical to the compartments 19 to 27 as shown on the face portion of the member 14. The washer 50 abuts against the outer end of the bearing portion 41, and the disk cover member 51 is securely mounted on the shaft 13 by means of the nut 52, which cover member 51 is adapted to rotate at all times with the portion 14, and the inturned portion 46 has along the outer edge thereof the indicating characters A to R inclusive to correspond to the compartments on the face of the member 14. This member 51 has the door 54 pivoted as at 55 and 56 so that when a customer desires a particular article of merchandise, and this article of merchandise is displayed in the section A on the member 14, then the casing 43 will be rotated until the article under the letter "A" registers with the arrow 57 on the cover member 51, at which 20 25 30 time the door 54 may be opened and the desired article of merchandise will be registering with this door and can be removed from the casing.

In the drawings and specification I have 35 set forth a preferred embodiment of my invention, and although specific terms are employed they are used in a generic and descriptive sense only, and not for purposes of limitation, the scope of the invention being set 40 forth in the appended claims.

I claim:

1. In an exhibiting device, a circular member, a shaft on which the circular member is fixedly mounted, means for driving the circular member and said shaft, a bearing for said shaft, a plurality of sections marked off on the face of the circular member, means for securing articles to the face of said circular member, a casing loosely mounted on 45 50 55 said bearing and having a plurality of compartments therein, into which articles similar to those exhibited on the face of the circular member may be stored, a cover member for said casing fixedly mounted on said shaft, a door in said cover member thru which entrance to selected compartments in the storage casing may be effected.

2. In an exhibiting device, a standard, a bearing member mounted on top of said standard, a shaft mounted in said bearing member, a circular exhibiting device fixedly secured on said shaft, a pulley mounted on the rear face of the circular exhibiting member, an electric motor mounted on said standard, and means cooperating with said pulley

and motor to impart rotation to the circular member and the shaft on which the same is mounted, a casing member loosely mounted on the said bearing portion, a cover for said casing member fixedly secured on said shaft, a door in said cover member adapted to be opened to admit entrance into one of the compartments in said storage casing.

3. In an article exhibiting device, a standard, a bearing portion mounted on said standard, a shaft rotatably mounted in the bearing portion, a circular exhibiting member secured to one end of said shaft, means for imparting rotation to said circular exhibiting member, the face of said circular exhibiting member being divided into sections, means for securing articles of merchandise in said sections, a circular casing corresponding in size to said exhibiting member mounted for rotation at will on the bearing member which supports said shaft, said casing being divided into compartments corresponding to the sections marked off on the face of the exhibiting member, a cover member for said casing fixedly secured to said shaft and being adapted to rotate with said exhibiting member, a door for said cover member through which access may be had to any selected compartment in said casing.

In testimony whereof I affix my signature. 95
JACK E. LINEBERGER.
